INDEX TAB

Lee E. Auckley, Milwaukee, Wis.

Application January 2, 1947, Serial No. 719,708

6 Claims. (Cl. 40—23)

1

This invention relates to filing systems and has more particular reference to index tabs used on file guides or any type of flat file cards or sheets for signalling or identification purposes.

None of the index tab devices heretofore devised has satisfied the long felt need for a satisfactory tickler or follow-up file tab.

It was formerly a common business practice to place one copy of an order, letter, or other record in an alphabetical file and to file another in a tickler file by follow-up date so that the record could be brought to the attention of the proper person on a specified future date.

Since this necessitated making and handling two copies of each record and maintaining two sets of files, a single file follow-up system was subsequently devised. The records were kept in folders arranged in alphabetical order according to firm names, and each folder was equipped with a signal device or tab cooperable with a date scale printed on the folder to indicate the desired follow-up date on which the record was next to be consulted. This system thus combined the previously used separate alphabetical and tickler files into one.

The signals or tabs previously employed usually took the form of folded celluloid or metal signal clips slidably received on the upper edges of one cover of the folders. An aperture in the front face of the clip framed one of the date scale numbers on said cover to disclose the follow-up date.

Thus the positions of the various tabs toward the right or left side of the file was intended to give at a glance an approximate indication of the follow-up dates of records kept in the folders.

Despite the fact that some indication of the approximate follow-up dates was afforded by these past types of index tabs, it was still necessary to pull up individual folders to render their date scales visible above the top edges of adjacent folders in order to determine the precise dates for which they were tabbed. In other words, there has never been a practical index tab for the purpose described by which the exact follow-up date was readily visible and changeable without detachment of the tab from the folder.

Another objection to existing types of tabs was that their adjustability was attained at the expense of security of attachment and the tabs were frequently accidentally knocked off the folders to which they were attached, or otherwise displaced, so that much of the time saved by the use of index tabs was lost in seeking stray tabs and the folders from which they had become detached.

2

On the other hand, tabs which effectively resisted accidental displacement were expensive and difficult to adjust.

By contrast, it is an object of this invention to provide a readily adjustable index tab which will remain securely in place and which presents a dated flagging signal above the edge of the sheet or folder to which it is attached so that it will be readily visible at all times.

Another object of this invention resides in the provision of a filing tab for tickler or follow-up files having a readily adjustable date signaling device thereon to give immediate and positive visual indication of the follow-up date on which the file is to be consulted.

It is another object of this invention to provide an index tab for use on the folders of tickler files which tabs at all times present readily adjustable and interchangeable dated signals to view above the edges of folders in the file, the dates on which are adapted to correspond with dates on the date scales of the folders to which they are attached to indicate at a glance by their position to the left or right in the file drawer the approximate order in which the contents of the folders in the file drawer are to be consulted.

Still another object of this invention resides in the provision of an index tab of the character described with a readily adjustable date signaling device and a pocket into which a name tag or card may be readily inserted and held, along with said signaling means, completely exposed to view above the edges of surrounding file folders or sheets.

With the above and other objects in view, which will appear as the description proceeds, this invention resides in the novel construction, combination and arrangement of parts substantially as hereinabove described and more particularly defined by the appended claims, it being understood that such changes in the precise embodiment of the herein disclosed invention may be made as come within the scope of the claims.

The accompanying drawings illustrate several complete examples of the physical embodiment of the invention constructed according to the best modes so far devised for the practical application of the principles thereof, and in which:

Figure 1 is a perspective view of a file drawer containing a plurality of file folders and illustrates the application of the index tab of this invention to some of the folders;

Figure 2 is a front elevational view, partly in section, of an embodiment of the index tab of this invention;

Figure 3 is a side view of the embodiment shown in Figure 2;

Figure 3a is a side view of a slightly modified version of the tab shown in Figure 2;

Figure 4 is an exploded view of the embodiment of the index tab shown in Figure 2;

Figure 5 is a front elevational view of another embodiment of the index tab of this invention;

Figure 6 is a partial exploded view showing a modification of the Figure 2 embodiment; and

Figure 7 is a perspective view of a portion of a spring showing a further modification of the embodiment depicted in Figure 6.

Referring now more particularly to the accompanying drawings, in which like numerals indicate like parts throughout the several views, the numeral 4 represents generally an index tab fabricated in accordance with the principles of this invention and suitable for attachment to the date numbered edge of a file folder 5 or the like. This tab comprises essentially a clamp portion 6 and a signal portion 7.

The clamp portion of the tab is made up of a front clamp member 8, a rear clamp member 9, a pintle 10 hingedly connecting the clamp members medially of their ends and an expansion spring 11. Both the front clamp member 8 and the rear clamp member 9 are preferably formed as one piece stampings of light sheet material, such as steel.

The portions 12 of the clamp members beneath the pintle engage substantially flatwise with one another and constitute cooperating jaws capable of gripping an edge portion of a flat sheet or file folder interposed between them under the tension of the spring 11.

Two or more inwardly directed spurs 13 project from the lower edge of one of the jaws and are adapted to bite into one side of the sheet to which the clamp is secured, so as to insure a tight grip on the sheet by which the clamp resists accidental displacement. The other jaw may be provided with like spurs, or it may be provided with wells or apertures 14 aligned with the spurs 13 on its opposite member. The provision of both spurs and wells in this manner will cause the clamp to form a dimple in a relatively thin sheet to which it may be attached, thus compensating for the fact that the clamp would otherwise be less securely attached to such a sheet because of the lesser spring tension available to hold it thereon.

Again, by providing spurs and wells in this manner the tab of this invention may be used with a guide sheet or folder having a row of spaced apart perforations inwardly on its margin, so that the spurs, cooperating with these perforations, will serve to locate the tab at any one of a number of exactly predetermined positions along the edge of the sheet and will securely hold it there.

One of the jaw members is also provided near its top with a pair of inwardly struck lugs 40, while the other jaw has mating apertures 41 in which the lugs are received. These lugs serve as stops, adapted to abut the edge of a sheet 5 on which the index tab is installed to prevent placement of the tab too low on the sheet so that the lower part of the signal portion 7 will not be obscured by the upper edge of files in front of the tabbed sheet.

The jaw portion 12 of the front clamp member 8 has a suitably located aperture 42 therein of a size and shape to disclose and frame one of a series of numbers 43, corresponding to dates, which may be printed along the marginal edge

of one of the covers of a file folder 5 to which the index tab is to be secured. In the present case the date scale is shown on the rear cover of the folder and the tab of this invention is correspondingly clamped over the numbered edge of the rear cover of the folder. The numbers on all the folders start with the numeral 1 at the left and run consecutively to the numeral 31 at the right. Also, the front cover of the folders is understood to be shorter than the back cover so that the date scale shows on the folders despite their closed conditions.

The upper portions 15 and 15' of the front and rear clamp members, respectively, form, in effect, a handle or tab for the clamp. If desired, the rear handle may be reinforced against transverse bending by means of vertical ribs 20 stamped therein.

Ears 16 extend inwardly from either side of the handle of each clamp member, at right angles to the body of the handle, to form hinge members for the clamp. The ears 16 are so spaced that those on one clamp member overlap those on the other. Aligned holes 17 in the ears accommodate the pintle 10 which serves as a medial hinge pin for the clamp.

Offsets 18 and 18' in the front and rear clamp members 8 and 9, respectively, serve to space the handles of the clamp outwardly of the jaws 12 thereof, so that the handles may be brought together to effect spreading of the jaws of the clamp.

The spring 11 has a U-shaped cross section, and is disposed between the handles with the base 35 of the U resting on the offsets 18 and 18', and the legs of the U straddling the pintle 10 and in engagement with the inner surface of the handles to bias them outwardly and thus effect converging clamping bias of the jaws 12.

It will be seen that the spring 11 is retained in position by the offsets 18 and 18', the inner surfaces of the handles 15 and 15' and the pintle 10 and is restrained against transverse displacement in a direction parallel to the pintle by the fact that its width is substantially equal to the transverse distance between the innermost ears 16, against which its ends abut.

In the embodiment of the index tab of this invention shown in Figure 6, the pintle 10 has been eliminated, and the spring 11 formed with an integral trunnion extension 10' at each end thereof, near the base of the U. These trunnion extensions 10' may be bent to a channel-shape, as shown in Figure 6, or to a triangular cross section, as shown in Figure 7.

In either event the trunnion extensions engage in the holes 17 of the ears 16 to serve as hinge pins. It will be readily apparent that the ears 16 not only hold this form of spring from becoming detached from the clamp but also serve to prevent transverse displacement of the spring.

The signal portion 7 of the tab of this invention comprises essentially a cover-like retaining member 22 and a pair of signal discs 23 and 23'. The retaining member is preferably fabricated as a unitary stamping from sheet material of the same kind as that from which the clamp members are made.

Parallel flanges 24 and 24' at the top and bottom of the retaining member, respectively, project rearwardly and toward one another to cooperate with a forwardly bent flange 25 on the upper edge of the front clamp member 8 and the offset 18 therein to hold the retaining member in place on the handle portion of the front clamp

member, with the discs 23 and 23' confined snugly between said parts.

It will be seen that the retaining member may be readily installed on the front clamp member 8 by engaging the flanges 24 and 24' with the upper flange 25 of the front handle 15 and the offset 18 thereof and sliding the retaining member parallel to the hinge axis. The retaining member may be quickly removed from the clamp by sliding it in the opposite direction.

A pair of trunnions or bearings 26, struck outwardly from the handle portion 15 of the front clamp member 8, serve to journal the signal discs 23 and 23', which have holes 27 at their centers to receive these trunnions. The trunnions are located along a line parallel to the hinge axis of the clamp, and their axes are transverse to the surface of the handle 15 from which they are struck.

The signal discs 23 and 23' are preferably made of plastic, colored if desired, and may be formed with a milled or serrated edge to facilitate rotational adjustment of them. A series of numbers is delineated on one face of each disc, although other appropriate indicia may be used if desired.

The discs are journalled on the trunnions 26 with their rear surfaces adjacent to the outer surface of the tab 15. Since the trunnions project forwardly beyond the front face of the discs, the retaining member for the discs is provided with a channel-shaped ridge or recess 29 extending thereacross to accommodate the trunnions. The retaining member 22 not only holds the discs against forward displacement off their trunnions but is so connected with the front handle member by its flanges as to be drawn against the discs and thereby create sufficient friction between the surfaces of the discs and the metal surfaces between which they are confined as to prevent accidental rotational displacement of the discs from the positions to which they are adjusted.

A window or aperture 30 in the retaining member exposes the adjacent edges of the discs, and any one or two digit number may be made visible through the aperture 30 by rotating the discs to bring the appropriate number on each of them into register with the aperture.

A cutout 31 at each side edge of the handle portion 15 of the clamp and the retaining member 22 exposes the milled periphery of the discs adjacent thereto to provide convenient access to the discs for rotational adjustment. It will be understood, of course, that when numbers are delineated on the discs the discs will have to be provided in matched pairs so that the numerals on each disc will be right-side-up as they are brought into register with the aperture 30.

The lower portion of the retaining member 22 cooperates with the handle portion 15 to provide a pocket 32 adapted to hold an index label 33. An inwardly bent ridge 34, extending transversely across the retaining member and contacting the outer surface of the handle or tab 15 defines the top of the pocket, and the flange 26' at the bottom of the retaining member provides the bottom of the pocket.

A dimple or rib 35, stamped outwardly from the lefthand side of the tab 15 and contacting the underside of the retaining member defines one end of the pocket, and a similar dimple or rib 35', stamped inwardly from the surface of the retaining member 22 and contacting the front of the handle portion 15 serves to define the opposite end of the card pocket. The ribs 35 and 35' cooperate with each other and with the flange 26'

and ridge 34 to prevent accidental displacement of a card in the pocket. The face of an index card 33 held in the card pocket so formed is visible through an aperture 31 in the retaining member.

When using signal discs colored in accordance with a predetermined color code, it is sometimes necessary to change from one set of colors to another. In this event, the retaining member is first slid flatwise to the right off the front tab. It will be noted that the retaining member described above is removable only when slid in one direction, from left to right in the case of the structure illustrated, since the ribs or dimples 35 and 35' will otherwise interengage and prevent withdrawal of the retaining member. Next the signal discs thus freed are removed from their trunnions and a pair of signal discs having the desired colors and/or characters on their faces substituted therefor. The retaining member is then again slid into place on the tab to hold the discs on their trunnions.

To change index cards, it is only necessary to slide the retaining member to the right a little less than half-way off the tab to enable the index card in the pocket to be slid in one direction or the other past the ribs or dimples 35 or 35'. A new card is then inserted before sliding the retaining member back to its operative position. Thus, it will be noted, substitution of index cards is accomplished without danger of the signal discs becoming detached from their trunnions.

To secure the tab to the proper file folder or guide sheet, it is necessary only to squeeze together the handle portions 15 and 15' to spread the clamp jaws to thus enable their application to the sheet. The tab may then be moved along the edge of the folder or sheet to bring the proper follow-up date into register with the aperture 42, and when the handles are released the clamp jaws will close and immediately secure the tab in position. The signal discs are then rotated to proper positions, bringing up a numeral in the aperture 30 identical with the date over which the tab is placed on the folder.

Thus, it will be seen that the file tab of this invention provides at a glance an immediate approximate date signal by virtue of its lateral position in the file drawer, while the signal discs afford an accurate indication of follow-up date which will be at all times visible to the file clerk without requiring him to move or separate the file folders. The double-check thus provided is also of great value in the event the index tab is accidentally removed or displaced from its proper file folder.

The index card pocket feature permits records to be filed alphabetically as well as by follow-up date, and provides an instantly visible index signal.

The modified embodiment of the index tab of this invention shown in Figure 3a is particularly useful where the height of the file drawer places a limitation upon the height of the index tab which may be used. In this modification the handles 15 and 15' are both bent at a backward angle with respect to the jaws 12. The tab portion thus requires somewhat less "headroom" and is more readily visible when used on folders filed in lower drawers, where the file clerk must look downward as well as rearward.

It will also be understood that in some instances it may be desirable to use only one signal disc, or to use an index tab having no signal discs but only an index card pocket, such as that shown in Figure 5. In either case the advantages of the

readily movable clamp mechanism of this invention will be realized and the resulting index tab will provide for quick and convenient adjustment or replacement of whatever signal means are employed.

From the foregoing description, taken in connection with the accompanying drawings, it will be readily apparent that this invention provides a simple and inexpensive adjustable index tab which will enable a single file to be used both as an alphabetical and a follow-up file and which will carry readily adjustable date signalling means above the level of the edges of surrounding file folders.

What I claim as my invention is:

1. In an index tab of the type having flat jaws hingedly connected together for flatwise swinging motion toward and from one another and adapted to receive the marginal edge of a sheet between them: a relatively flat extension on each jaw providing a handle thereon; spaced substantially parallel shoulders on one of said handles, one of said shoulders being provided by an offset adjacent to the hinge connection between the jaws by which the handles are disposed in spaced apart relationship when the jaws are closed thereby enabling the jaws to be spread apart by convergence of the handles; a retaining plate having a pair of substantially parallel flanges engaged over said shoulders to detachably connect the plate with the handle, detachment of the plate requiring relative motion between the plate and the handle in a direction parallel to the length of the flanges; and cooperating means on the retaining plate and said handle for retaining a signal device on the tab between the plate and said handle with said signal device visible through an aperture in the plate.

2. The index tab of claim 1 further characterized by the fact that said retaining plate is provided with a ridge spaced from and substantially parallel to one of the flanges thereon, said ridge cooperating with said flange to define a pocket wherein a signaling card is adapted to be removably retained to be visible through another aperture in the retaining plate.

3. The index tab of claim 2 further characterized by the fact that said retaining plate is provided with an inwardly impressed rib at one side thereof and said handle is provided with an outwardly impressed rib at the opposite side thereof, said ribs having a depth sufficient to cooperate with one another in frictionally holding the retaining plate against detachment and in defining said card pocket.

4. The index tab of claim 1 further characterized by the provision of trunnions struck outwardly from the handle and adapted to rotatably journal signal discs, and by the provision of a recess in said retaining plate into which said trunnions project so that the discs are frictionally retained against rotational displacement between the retaining plate and the handle, a portion of each disc being visible through an aperture in the retaining plate.

5. In an index tab of the type adapted to be detachably clamped about the marginal edge of a substantially flat sheet and having signal means extending above the edge of said sheet: a pair of unitary clamp forming members, the lower portions of which comprise substantially flat jaws; hinge means above the lower portions of said clamp forming members and connecting the

members to enable said jaws to flatwise engage a sheet placed therebetween, the portions of the clamp members above the hinge means comprising a pair of handles; an offset on at least one of said clamp forming members whereby its handle portion is displaced outwardly with respect to its jaw portion and away from the other handle portion but substantially parallel thereto so that said handle portions will not materially interfere with access to files adjacent to that to which the index tab is clamped, said handle portions providing for spreading the jaws by converging motion against yielding outward bias; means located in the space between the handle portions of said clamp members and reacting

against the same for yieldingly urging the jaws together toward flatwise engagement; and means for holding a signaling device on the handle portion of said one clamp forming member, comprising a unitary retaining member having its upper and lower edges adapted to cooperate with the upper edge of said handle forming portion and with the offset thereon, respectively, to thus enable said retaining member to be removed from said clamp forming member by transverse sliding motion, said retaining member having apertures therein rendering the signal means visible.

6. In an index tab of the type having flat jaws hingedly connected together for flatwise swinging motion toward and from one another and adapted to receive the marginal edge of a sheet between them: a relatively flat extension on each jaw providing a handle thereon, one of said handles having an offset adjacent to the hinge connection between the jaws, by which the handles are disposed in spaced apart relationship when the jaws are closed over the marginal edge of a sheet between them; spaced shoulders on one of said handles, said shoulders being substantially parallel to one another and to the hinge axis; a retaining plate having substantially parallel flanges engaged over and cooperating with said shoulders to detachably connect the plate with the handle, detachment of the plate requiring relative motion between the plate and the handle in a direction parallel to said shoulders; cooperating means on the retaining plate and the handle having the shoulders thereon for retaining a signal device on the tab between the plate and said handle with the signal device visible through an aperture in the plate; and means connected with said handles for releasably holding the jaws closed over the marginal edge of a sheet between them.
